CHARLES E. DE VALIN, OF BALTIMORE, MARYLAND.

Letters Patent No. 96,403, dated November 2, 1869.

IMPROVED MACHINE FOR THREADING BOLTS.

The Schedule referred to in these Letters Patent and making part of the same.

To all whom it may concern:

Be it known that I, CHARLES E. DE VALIN, of Baltimore, in the county of Baltimore, and in the State of Maryland, have invented certain new and useful Improvements in Automatic Bolt and Screw-Cutters; and do hereby declare that the following is a full, clear, and exact description thereof, reference being had to the accompanying drawings, and to the letters of reference marked thereon, making a part of this specification.

The nature of my invention consists in the construction and general arrangement of an "automatic bolt and screw cutter."

In order to enable others skilled in the art to which my invention appertains, to make and use the same, I will now proceed to describe its construction and operation, referring to the annexed drawings, in which—

Figure 1 is a plan view of the entire machine;

Figure 2 is an end view of the rear side of the machine, showing a portion of the feeding-mechanism;

Figure 3 is a side view of a portion of the main shaft, showing the mechanism for moving the same longitudinally forward and backward;

Figure 4 is an inside view of one of the side plates of the machine, showing the guides;

Figure 5 is a side view of the feeding-bar and the mechanism connected with the same;

Figure 6 is a front view of the die-box;

Figure 7 is an inside view of the die-box, the front plate being removed, showing the manner of operating the cutting-dies;

Figure 8 is also an inside view of the die-box, the front plate and circumferential ring being removed;

Figure 9 is a side view of a tumbler-stop, used to close the dies in the die-box;

Figure 10 is a vertical section of the die-box, attached to the front end of the main shaft;

Figure 11 is an enlarged perspective view of one of the cutting-dies;

Figure 12 is a side view of a portion of the feeding-mechanism, the balance of said mechanism being shown in fig. 2;

Figure 13 is a vertical section of a portion of the face-plate, showing the manner of holding the bolts that are to be cut; and

Figure 14 is a horizontal section of a portion of the face-plate, showing the dovetailed recess and opening in the same.

A represents the main shaft, revolving in three bearings, B, B', and B''. These three bearings are sustained by one bed-plate, the whole constituting one piece, and supported by a suitable frame-work.

D represents the die-box, for holding three cutting-dies or cutters, a a, in this case, but, if desirable, the

die-box may be constructed to hold a greater or less number of cutting-dies.

The die-box D is cylindrical for a distance, from the front end, a little greater than the depth of the cutting-dies a a, and thickness of the sliding carrier-bar b. In this cylindrical portion of the die-box there are three rectangular slots or recesses, open at the front end of the die-box, and extending through from the outer circumference of the cylindrical part to a hole which is bored at the centre, in the direction of the axis of the die-box, large enough in diameter to pass freely over the largest bolt the machine is intended to cut. These slots or recesses are at equal distances apart, and have a radial direction.

The cutting-dies a a are rectangular in their cross-section, and of such length, that when closed, the outer ends come even with the outside circumference of the cylindrical part of the die-box, and their inner ends, forming the die proper, are in the position for cutting the desired thread.

There are open spaces between the inner ends of the cutting-dies, as seen in figs. 7 and 8, for the escape of chips.

At the front of the dies the thread is not full, that is, the ends of the teeth are cut away, so that a full thread is not made until the bolt has passed several threads in the cutting-dies.

The cutting-faces of the teeth, at the front, are also chamfered off, as seen in fig. 11, so as to make acute angles for the cutting-edges.

On the front end of the die-box there is a circular disk, c, or plate, with a hole at the centre to correspond with the hole in the die-box, secured to the die-box by screws with countersunk heads, as seen in fig. 6. This plate confines the dies to their respective slots or recesses in the die-box.

At the rear end of the cylindrical part of the die-box, there is a circular flange or collar, d, continued entirely around the die-box, with its front face at right angles with the axis of the cylindrical part of the die-box, and parallel with the circular disk c on the front of the die-box.

Between this flange and the front plate or disk there is contained a ring, e, of the same outside diameter as the collar or flange d, and of the same inside diameter as the cylindrical part of the die-box containing the cutting-dies.

At equal distances apart, on the inside surface of the ring e, there are recesses, as seen in fig. 7, one for each cutting-die, so that when the dies are brought opposite the recesses, they have room to move outward far enough to allow the bolt, which has been cut, to be withdrawn.

The sides of these recesses in the ring, for the cut

ting-dies, form inclined planes, and the outer ends of the cutting-dies are rounded, so that when the die-box is revolved, and the ring held stationary, the outer ends of the dies coming in contact with the inclined planes, the dies are gradually closed until the circular part of the inside surface of the ring is in contact with the outer ends of the dies.

In the rear face of the ring *e* there is a slot or recess for the reception of the sliding carrier-bar *b*. This sliding carrier-bar is confined to its recess or slot by coming in contact with the front face of the flange or collar *d* before mentioned.

In the front face of this collar or flange there is a cam-groove *f*, continued all the way round, and following such directions, that when the ring *e* has closed the cutting-dies, one portion of the groove, farthest from the axis of the die-box, is opposite the sliding carrier-bar *b*.

This bar passes freely in a radial direction in the slot in the ring *e*, and has a pin on its rear side, which fits in the cam-groove *f* of the flange or collar *d*, as seen in fig. 8.

When this pin occupies a position in the cam-groove farthest from the axis of the die-box, the outer end of the sliding carrier-bar *b* extends beyond the outer surface or circumference of the ring *e* its greatest distance, and when the pin is in that part of the groove nearest the axis of the die-box, the carrier-bar is drawn to its position nearest the axis of the die-box.

The outer end of the sliding carrier-bar *b* has an elbow, turned at right angles to the part occupying the slot, and parallel with the axis of the die-box, as shown in figs. 1 and 10.

To the rear of the flange or collar *d* of the die-box there is a boss, by which the die-box is secured to the front end of the main shaft *A*.

In suitable openings at the bottoms of the recesses or slots for the cutting-dies *a a*, are inserted springs *i i*, the ends of which enter notches in the rear sides of the dies, and have a tendency to force the dies apart in radial directions.

The main shaft *A* has a hole bored in the front end, corresponding with the hole at the centre of the die-box, deep enough to clear the bolts to be cut.

On the main shaft *A*, and between the first and second shaft-bearings *B* and *B'*, from the front, there is a geared driving-wheel, *E*, which has a feather in its bore, fitting loosely in a key-seat in the main shaft, the key-seat being of sufficient length to allow the shaft to move longitudinally through the geared driving-wheel as far as necessary to cut the longest bolt intended to be cut.

The geared driving-wheel *E* is prevented from moving longitudinally with the shaft by the two bearings *B* and *B'*, that it fits between.

By means of the feather in the wheel *E*, the shaft is revolved with the wheel. Between the second and third bearings, *B'* and *B''*, there is situated a yoke, *F*, on the main shaft *A*, which yoke is confined between two collars, *g g*, on the shaft, but the shaft is free to revolve in the yoke.

Through the other end of the yoke *F*, under the main shaft, and parallel with it, there is a screw, *G*, for advancing the main shaft, revolving in bearings in the frame of the machine.

In the yoke *F*, over the screw *G*, there is a half or other portion of a nut, *h*, which moves up and down in a slot cut through the yoke, transverse to the screw.

This nut has two pins or arms, *o o*, one on either side, which, when the nut is in gear with the screw, pass under adjustable guides *k k*, parallel with the screw.

There is a horizontal shaft passed through the yoke *F*, above and transverse to the screw *G*, on each end of which, and close up against the sides of the yoke,

there is a bent lever, *l*, secured at its angle to the end of the shaft.

The upper ends of these levers *l l* have lugs on the outsides, and the lower ends have oblong holes through which the pins, or arms *o* of the half nut *h* pass, as seen in fig. 3.

Parallel with the screw *G*, and on both sides of the yoke, there are two side-plates secured to the frame of the machine, and through these side-plates are cut two slots, parallel with the screw *G* and main shaft *A*, for the reception of the shanks of the guides *k k*. These guides are two in number, secured, one to each side-plate, on the inside, next the yoke. Each guide is formed of two pieces. The rear piece of each guide, as seen in figs. 1 and 4, is a bar placed parallel with the screw and the main shaft, and connected at its rear end to a flange, and having a space between it and said flange for the passage of the parallel bar of the forward piece of the guide.

The flange bears against the side-plate, and has a rectangular shank, which is of the same width as the slot in the side-plate. On this shank are a screw-nut and washer, which projection the outside of the side-plate, and are for the purpose of securing the guide in its proper position.

One or both of these rear pieces is allowed to move freely along the slot in the side-plate, and is provided with a very flexible spring, *m*, shown in fig. 1, for forcing its shank against the rear end of the slot in the side-plate. When only one of these rear pieces is provided with a spring, the rear piece of the other guide is secured firmly in its proper position on the side-plate.

The rear end of the parallel bar of this rear piece of the guide *k* is not square, but inclined downward and backward.

The forward piece of each guide is composed of a parallel bar of the same width as the bar of the rear piece described, and of such thickness that it may pass between the rear bar and its flange. The bar of the forward piece is even and parallel with the bar of the rear piece, and is provided with a flange, shank, screws, nuts, and washers for securing it to the guide-plate, the one slot in each side-plate answering for the shanks of the two pieces of the guide.

On the flange of the forward piece of each guide there is a projection or extra thickness of flange, *n*, underneath the forward end of the parallel bar, forming an inclined plane, which inclines forward and upward, as seen in fig. 4, and so far from the forward end of the parallel bar, that the pin, or arm *o* of the half nut *h*, before mentioned, may pass between them.

This same projection or extra thickness of flange continues in front and above the forward end of the parallel bar, with room for the before-mentioned pin of the half nut to pass over the end of the parallel bar, and projects so far in toward the yoke *F*, that the lug on the bent lever *l*, on the yoke, may strike it as the yoke moves forward.

On the top, and passing down to the rear of this flange, there is a spring, *p*, for the lug of the bent lever before mentioned to press upon as it advances forward.

On the rear end of the screw *G*, to the rear of its bearing, is secured a gear-wheel, *H*, and suspended between said wheel and bearing, on the screw, is an arbor, *I*, forming a sector, and revolving about said screw as a centre.

The arbor *I* has a hole at each end of its arc, as seen in fig. 2, for a screw-stud, *r*, which has a nut at each end, and a shoulder at the end which goes through the arbor.

The screw-stud *r* extends to the rear of the arbor *I*, and may be placed in either of the holes before mentioned.

On the screw-stud *r* is placed a gear wheel, *J*, in

the same vertical plane with the gear-wheel H, on the screw, and gears with it.

The gear-wheel J is extended at its hub to the rear, forming a sleeve, on which is keyed another gear-wheel, K.

The nut and washer on the rear end of the screw-stud r are for the purpose of keeping the gear-wheels on the stud, at the same time allowing them to revolve freely around the stud.

The gear-wheel K, on the sleeve, is a changeable wheel; that is, it may be substituted by a larger or smaller gear-wheel, and gears with another wheel, L, on the main shaft A.

This last-mentioned gear-wheel (L, on the main shaft,) extends, at its hub, forward to the rear main-shaft bearing B², forming a sleeve, with flange at the forward end, over which the cap of the bearing B² extends, so as to form a recess for the flange of the gear-wheel to revolve in, at the same time preventing any motion in the longitudinal direction with the main shaft.

The gear-wheel L, situated on the rear end of the main shaft, is provided with a feather in its bore, which is inserted into a key-seat in the main shaft, as seen in fig. 2, and the wheel is revolved by the main shaft, said key-seat extending far enough forward to allow the required longitudinal motion of the main shaft.

The arbor I, before mentioned, is provided with a circular slot between the two holes, for the screw-stud r, through which a screw-bolt s is passed and screwed into the end of the machine-frame.

On this screw-bolt there is a washer, t, between the arbor and the frame of the machine, of such thickness that when the bolt is screwed up, the arbor is held in position between the head of the bolt s and the washer t.

Secured to the forward side of the rear main-shaft bearing B², are two springs, u u, one on each side of the main shaft, against which the lugs of the bent levers l l, on the yoke, strike, as the main shaft moves to the rear.

Around the main shaft A is wound a strong spring, M, the rear end of which bears on the forward collar g on the shaft, and the forward end of the spring bears against a loose washer placed on the shaft, and against the rear end of the main-shaft bearing B¹.

Alongside of the main shaft A there is a driving-shaft, N, revolving in bearings parallel and in the same horizontal plane with the main shaft, and has a cone-pulley, O, and a geared pinion, P, secured to it.

This pinion gears with the geared driving-wheel E on the main shaft A.

The driving-shaft N has two collars, v v, at its rear bearing, which prevent the shaft moving longitudinally.

On the front of the frame of the forward main-shaft bearing B there is a stop, R, oscillating on a pin in two lugs secured to the frame. This stop is made triangular in its vertical section, made parallel with the main shaft. Its upper face is horizontal, its rear face is vertical, and its front face is inclined downward toward the rear, as seen in fig. 9.

The tumbler stop R is placed at such a distance from the centre of the main shaft, that when the boss of the die-box D is against the forward main-shaft bearing B, the sliding carrier-bar b is nearest the axis of the die-box, and the ring e of the die-box is in that position at which the dies are open; the sliding carrier-bar will strike on the upper face of the tumbler-stop, when the die-box is revolved in the proper direction, and remain in contact until the cutting-dies are closed, when the sliding carrier-bar will have moved outward from the die-box far enough to allow the elbow of the sliding carrier-bar to pass on the outside of the tumbler-stop.

In front of the stop R, just described, there is another adjustable stop, S, formed of a rectangular bar, bent up at right angles at the forward end, resting on

the bed-plate, near the front end, under the main shaft. This adjustable stop is placed parallel with the main shaft, and passes through an opening at the bottom of the forward frame, and under a clamp placed at the front end of the bed-plate. This clamp is provided with a set-screw, holding the stop in position.

That part of this adjustable stop S which is bent up toward the main shaft, is of such height that when the dies in the die-box are closed, and the sliding carrier-bar b is out to its farthest position from the axis of the die-box, as the die-box moves forward, the carrier sliding-bar will strike the adjustable stop, and be retained against it until the dies are opened, and the sliding carrier-bar is in its position, nearest the axis of the die-box, when the bar will pass the adjustable stop on the inside, between it and the die-box.

On the opposite side of the main shaft from the driving-shaft N, extending along the edge of the bed-plate, and beyond the forward end of it, there is a shaft, T, parallel with the main shaft, revolving in suitable bearings, secured to the bed-plate.

On the forward end of this shaft there is a circular disk, V, forming a face-plate, movable along the shaft, but having a feather in its bore, fitting in a key-seat in the shaft, to prevent the face-plate from revolving around the shaft.

The face-plate V is provided with a hub and set-screw on the front side, as seen in fig. 1, for holding the face-plate in position on the shaft. This face-plate is for holding the bolts while they are being cut. It is of such outside diameter that its circumference extends beyond the centre of the die-box, situated on the main shaft.

At equal distances apart, in a circle equal in radius to the distance between the centre of the main shaft and the centre of the face-plate shaft, there are openings, w w, through the face-plate, for passing the bolts to be cut.

On the side facing the die-box, the face-plate V is dished out, leaving a hub at the shaft, and a rim, x, at the circumference, which rim extends equally on both sides of the circle, struck with a radius equal to the distance between the two shafts.

In the rim x, and through each opening w, there is a radial recess, y, cut to the full depth of the part dished out, and not quite to the outer circumference of the plate.

The sides of these recesses are dovetailed, and two dovetailed holding-dies z z are fitted in each recess, the two dies in each recess constituting a pair, and each pair of dies has two set-screws, for the purpose of forcing the two parts of the pair toward each other.

One set-screw, a', is in the outer rim of the face-plate, and the other set-screw, b', is in a circular plate, W, which occupies the part of the face-plate which is dished out between its hub and the rim x, all of said set-screws pointing in a radial direction in the face-plate.

The bolts to be cut are placed parallel with the main shaft, between the two parts of each pair of holding-dies z, a recess being cut across the side of each part next the bolt, and parallel with the main shaft.

The sides of these recesses are serrated, and of such form, that when they are set against the bolt, by means of the set-screws a' and b', the bolt will be held firmly, and parallel with the main shaft.

On the same shaft T as the face-plate V, in front of and against the rear bearing of the shaft, there is a ratchet-wheel, A', with the same number of square teeth as there are holding-dies in the face-plate V.

There is a pallet, c', which oscillates on the pin of a bracket, secured to the bed-plate, situated between the ratchet-wheel A' and one of the side-plates before mentioned, which is so constructed and situated that there are two teeth, one placed above the other, at a distance

equal to several teeth, and a part of a tooth of the ratchet-wheel A', as seen in fig. 12, and when the radial face of any one of the teeth of the ratchet-wheel rests against the upper tooth of the pallet c', the bolt, situated in one pair of the holding-dies z z, in the face-plate V, will have its axis in the same straight line with the axis of the main shaft A, and the lower tooth of the pallet will be withdrawn from the ratchet-wheel A', and when the upper tooth of the pallet is withdrawn from the ratchet-wheel, its lower tooth enters between two teeth of the wheel.

There is an arm of the pallet, c', extending on the opposite side of the pin of the bracket, from the side the teeth are on, which has a spring, d', under it, with a tendency to force the arm up.

To the front, and further along the same shaft, nearly opposite the second main-shaft bearing B', there is another ratchet-wheel, D', which has the same number of equal teeth as the first-mentioned ratchet-wheel A', and is keyed to the same shaft T. The teeth in this forward ratchet-wheel D' are reversed to the teeth in the rear wheel A', with the radial faces of the teeth even with the radial faces of the teeth of the rear wheel.

Between the forward ratchet-wheel D' and the side-plate, on the same side of the main shaft, there is an upright bar, e', rectangular in its cross-section. The upper end of this bar works through a strap, secured to the upper part of the side-plate, and the lower end works through a hole in the bed-plate.

On the lower end of this upright bar e', underneath the bed-plate, there is a stirrup-strap, f', swung on a pin, passing through the bar.

Secured at one end to the bottom of the bed-plate, there is a strong spring, g', with its other end bearing in the stirrup-strap f', which spring has a tendency to force the upright bar e' downward.

There is a pawl, h', swung on a pin in lugs secured to the side of the upright bar e', with a spring, i', bearing it, for forcing the pawl between the teeth of the ratchet-wheel D'.

On the opposite side of the ratchet-wheel D', there is another pawl, k', swung on a pin, in lugs secured to the bed-plate, and provided with a spring, l', which forces the pawl between the teeth of the wheel.

On the ratchet-wheel shaft T, against the rear side of the forward bearing, there is a collar, m', which prevents the shaft from moving forward, and there is a boss on the rear ratchet-wheel A', which prevents the shaft moving to the rear.

Secured to the yoke F, at the bottom, there is an arm, n', which extends under the side-plate, to its outer side, toward the ratchet-wheel shaft T.

On this arm there is a feeding-bar, o', resting on the bed-plate, and bearing against the outside of the side-plate, the rear end of which inclines upward and to the rear, and the front end passes under a shoulder of the upright bar e', before mentioned, as seen in fig. 5.

On the upper side of this feeding-bar o', there is an adjustable bar, p', with its forward end inclined downward and forward.

The feeding-bar o' is so constructed and situated, that when the yoke F is pushed to the rear as far as it can go, the rear inclined end of the feeding-bar forces the arm of the pallet c' downward, and withdraws the upper tooth of the pallet from the rear ratchet-wheel A', and causes the lower tooth of the pallet to enter between two of the teeth of the same ratchet-wheel.

To prepare the machine for cutting bolts of a desired length, diameter, and desired number of threads to the inch, it is necessary to place in the die-box D cutting-dies, with suitable thread and diameter, place a changeable-gear wheel on the sleeve of the gear-wheel J, on

the screw-stud of the arbor I, in order that the cutting-dies may be advanced the proper distance forward for each revolution of the dies around the bolt to be cut.

The arbor I is then moved around its centre until the changeable-gear wheel K comes into gear with the gear-wheel L, near the rear end of the main shaft A; then the screw-bolt s, passing through the slot in the arbor, is set up, and holds the arbor in place.

There are two holes in the frame of the machine for this screw-bolt, so that the arbor may be put in position for any of the different-sized changeable wheels.

We will suppose the yoke F is drawn back until the rear collar g on the main shaft strikes against the rear bearing B', and the boss of the die-box D against the forward main-shaft bearing B.

The forward pieces of the guides k k must be secured in position for throwing the half nut h out of gear with the screw G, when the cutting-dies have advanced as far as desired on the bolt to be cut.

The adjustable stop S, for the sliding carrier-bar b, must be set in position to open the cutting-dies, just before the half nut h is thrown out of gear with the screw. The bolts to be cut must be clamped in the holding-dies z z, by means of the radial set-screws a' b', in the face-plate V, so that as the face-plate revolves, the centres of the bolts will pass through the centre line of the die-box.

A belt on the cone-pulley O is to communicate motion from the driving-machinery to the cone-pulley revolving the same under, toward the main shaft. This motion is communicated, through the driving-shaft N, to the gear-wheel P, secured on it, and this gear-wheel causes the geared driving-wheel E, on the main shaft A, to revolve in the opposite direction, revolving with it the main shaft, the die-box D, and the gear-wheel L, near the rear end of the main shaft.

The wheel L gears with and revolves, in the opposite direction, the changeable-gear wheel K. This wheel being secured to the sleeve of the gear-wheel J, situated on the screw-stud r, in the arbor I, causes the wheel J to revolve with it in the same direction. The wheel J causes the gear-wheel H, on the rear end of the screw G, and the screw itself, to revolve in the same direction as the main shaft A.

The yoke F being in its rear position, the two springs u u, on the rear bearing B', will bear against the lugs on the bent levers l l, and force the upper ends of said levers forward, and the lower ends downward.

The lower ends of the bent-levers l l carry down with them the half nut h, by its pins or arms o o, causing it to gear with the screw G.

As the pins o o pass downward, they bear on the inclined ends of the rear pieces of the guides k k, and push them forward until the pins pass by the inclined ends of the guides.

The springs m, on the rear pieces of the guides, then force the rear ends of the guides over the tops of the pins in the half nut.

In the drawing, only one of the rear pieces of the guides has a spring, and in this case the other rear piece is set fast, so that the pin in the half nut will pass down by its rear end without touching it.

In this position of the yoke F, the inclined rear end of the feeding-bar o' will bear on the arm of the pallet c', so that the upper tooth is withdrawn from the rear ratchet-wheel A', and the lower tooth will be between two teeth of the same wheel.

We will suppose that the upright bar e' has been raised until its pawl h' has gone between two teeth of the forward ratchet-wheel D', and the spring g', under the bed-plate, is bearing the upright bar downward, with a tendency to revolve the ratchet-wheel D' over toward the main shaft. This will have caused

the rear ratchet-wheel A' to revolve in the same direction, until the radial face of one of its teeth bears against the lower tooth of the pallet c'.

We will also suppose the cutting-dies a a to be opened.

As the die-box revolves, the sliding carrier-bar b strikes against the tumbler-stop R, and the bar b and ring e are prevented from revolving, until the die-box has revolved far enough to bring the outer ends of the cutting-dies a a against the circular part of the inside surface of the ring, the dies having been gradually closed by passing over the inclined sides of the recesses in the ring e.

At the same time, the cam-groove f, in the flange or collar d of the die-box, has passed over the pin in the rear side of the sliding carrier-bar b, and moved said bar out in a radial direction, far enough for its elbow to pass over the outer side of the tumbler-stop R, when the sliding carrier-bar b and ring e will revolve with the other parts of the die-box.

As the screw G revolves, it advances the half nut h, its pins or arms o o passing under the guides.

The half nut carries with it the yoke F, and the yoke carries with it the main shaft A, die-box D, and feeding-bar o'.

There is always a little space left between the ends of the bolts to be cut and the forward end of the die-box, so that when the feeding-bar o' is advanced a short distance, and its inclined end left the arm of the pallet c', said arm rises by means of its spring, d', and the lower tooth of the pallet recedes from the rear ratchet-wheel A'. At the same time the upper tooth of the pallet enters between two teeth of the same ratchet-wheel.

The upright bar, with its pawl, descends, by means of the spring g', underneath the bed-plate, and causes the ratchet-wheels A' D', and face-plate V, to revolve in the direction before mentioned, until the radial face of one of the teeth of the rear ratchet-wheel A' has come against the upper tooth of the pallet c', and a bolt to be cut in the face-plate is opposite the centre of the die-box; also, the pawl k, on the opposite side of the forward ratchet-wheel D', falls in behind the tooth which has just passed its ends.

The pawl k is to prevent the ratchet-wheels and face-plate from revolving in the contrary direction.

As the parts before mentioned advance, the spring M, on the main shaft, is compressed between the forward collar g, on the main shaft, and the second main-shaft bearing B'.

At the same time, the feeding-bar o' is passing under the upright bar e, and the adjustable bar p', on the upper side of the feeding-bar, is raising the upright bar until its pawl k' takes in another tooth of the forward ratchet-wheel D'.

When the cutting-dies have cut a thread as far as desirable along the bolt, the sliding carrier-bar b being out to its greatest distance, strikes the adjustable stop S, and the bar b and ring e are arrested from revolving, until the die-box and cutting-dies have revolved far enough for the outer ends of the cutting-dies to enter the recesses in the ring.

The dies a a are opened gradually by their springs, and follow the inclined sides of the recesses in the ring.

When the dies have arrived opposite the middle of the recesses in the ring, the cam-groove f, in the collar d, of the die-box, will have passed over the pin in the rear of the sliding carrier-bar b, and have drawn the said bar inward far enough for the outer end of the bar to pass inside of the adjustable stop S.

By this time, the pins or arms o o, of the half nut h, in the yoke F, will have borne on the inclined parts of the flanges of the forward pieces of the guides k k, rising as they advance, until they pass above the forward ends of the guides.

When the pins in the half nut h have passed above

the guides, the half nut will have been lifted out of gear with the screw G, and the spring M, on the main shaft A, will force the yoke, main shaft, and die-box and feeding-bar back to the rear; the rear collar g, of the main shaft, striking against the rear main-shaft bearing B'.

The half nut falls into gear, and the ratchet-wheels and face-plate make a revolution equal to only part of a tooth of the ratchet-wheels. The machine is now in position for cutting another bolt.

The tumbler-stop R is so arranged, that if the sliding carrier-bar b should strike it in going back, the inclined end of the elbow of the carrier-bar will strike the inclined end of the tumbler-stop, and the stop will rise, when the carrier-bar revolves past, and the stop will fall into position by its own weight, and the carrier-bar will strike on the upper side in the next revolution.

A person stands in any convenient position, and takes out the bolts which are cut from the face-plate, by means of slackening up the outer set-screws a a, and puts in new bolts.

The screws b b, in the face-plate, are not altered unless bolts of different diameters are to be cut.

Having thus fully described my invention,

What I claim as new, and desire to secure by Letters Patent, is—

1. The combination of the die-box D, and its recessed ring e, flange or collar d, plate c, and sliding carrier-bar b, with the springs i i, and cutting-dies a a, all constructed as described, and operating substantially in the manner and for the purposes herein set forth.

2. The combination of the main shaft A and collars g g, with the yoke F, screw G, half nut h, and pins or arms o o, all constructed as described, and operating substantially in the manner and for the purposes herein set forth.

3. In combination with the yoke F and half nut h, the bent levers l l, constructed as described, and operating substantially in the manner and for the purposes herein set forth.

4. In combination with the bent levers l l, the springs u u, secured to the rear main-shaft bearing B', substantially as and for the purposes herein set forth.

5. The guide k, constructed as described, of two parallel bars, secured to a side-plate that runs parallel with the main shaft, substantially as and for the purposes herein set forth.

6. In combination with the guide k, the spring m, operating upon the rear bar of said guide, substantially in the manner and for the purposes herein set forth.

7. In combination with the guide k, the projection or flange n, and spring p, constructed as described, and operating substantially in the manner and for the purposes herein set forth.

8. The arrangement of the gear-wheels H, J, K, and L, arbor or oscillating plate I, screw-stud r, nut s, and washer t, all constructed as described, and operating substantially as and for the purposes herein set forth.

9. In combination with the main shaft A and die-box D, the oscillating tumbler-stop R, and adjustable stop S, constructed as described, and operating substantially in the manner and for the purposes herein set forth.

10. The face-plate V, constructed as described, with the openings w w, dovetailed recesses y y, rim z, and circular plate W, all substantially as and for the purposes herein set forth.

11. In combination with the face-plate V, the dovetailed dies z z, and radial set-screws a' b', all constructed as described, and operating substantially in the manner and for the purposes herein set forth.

12. The combination and arrangement of the face-

plate shaft T, ratchet-wheels A' D', pallets c' h' k', springs d' g' i' l', bar e', and stirrup-strap f', all constructed as described, and operating substantially in the manner and for the purposes herein set forth.

43. The feeding-bar o', constructed as described, with its rear end bevelled, and provided on its upper side with an adjustable bar, p', and operated by means of the arm n', on the yoke F, substantially in the manner and for the purposes herein set forth.

In testimony that I claim the foregoing, I have hereunto set my hand, this 20th day of August, 1869.

CHAS. E. DE VALIN.
